UNITED STATES PATENT OFFICE

CURTIS L. HOWSE AND CORNELIUS D. LOWELL, OF DETROIT, MICHIGAN, ASSIGNEES
TO DIAMOND POWER SPECIALTY CORPORATION, OF DETROIT, MICHIGAN, A COR-
PORATION OF MICHIGAN

BOILER CLEANER

Application filed June 25, 1923, Serial No. 647,667. Renewed March 26, 1930.

This invention relates to boiler cleaners and relates particularly to valves for automatically controlling the supply of cleansing fluid to a boiler cleaner unit.

5 The invention consists in the structural features and arrangement of parts hereinafter described and shown in the accompanying drawings wherein:—

10 Figure 1 is a view in sectional elevation showing a rotary blower pipe equipped with the hereinafter described control valve;

Figure 2 is a cross sectional view of the same on line 2—2 of Figure 1;

15 Figure 3 is a sectional view similar to Figure 2 but showing the open position of the valve;

20 Figure 4 is a cross sectional view similar to Figure 3 and showing the open position of the valve, the ported member of the valve having the position which it assumes preliminary to closing of the valve;

Figure 5 is an axial sectional view of an alternative form of the automatic control valve;

25 Figure 6 is a plan view of the same, omitting the valve casing;

Figure 7 is a cross sectional view on line 7—7 of Figure 5;

30 Figure 8 is an axial sectional view of still another alternative valve mechanism;

Figure 9 is a transverse longitudinal section of the same on line 9—9 of Figure 8;

35 Figure 10 is a cross sectional view of the same taken on line 10—10 of Figure 8;

Figure 11 is an axial sectional view of a further modification of the control valve mechanism;

40 Figure 12 is a plan view of the sliding and rotative sleeve controlling the steam supply in the construction shown in Figure 11;

Figures 13 and 14 are cross sectional views taken on line 13, 14—13, 14 of Figure 11 showing the valve opened and closed.

45 Referring first to the construction illustrated in Figures 1 to 4 inclusive, 1 designates a rotary blower pipe or unit having the usual series of discharge nozzles 1^a for steam or some other cleaning fluid. Said pipe is journaled in a packed bearing 2^a carried by a casing 2 at one end thereof. Within said casing

the blower pipe 1 is rigidly connected to a cylindrical head 3 having the inlet port 3^a, said head preferably having a screw threaded connection with the pipe 1, as indicated at 3^b. The head 3 has a reduced end portion 4 terminally closed as indicated at 4^a, said end portion being journaled in a packed bearing 5^a carried by the outer end wall 5 of the casing 2. The blower pipe 1, together with the head 3, may be conveniently described as a 55 rotative blower unit, or cleaner unit. Said wall is rigidly secured to the casing 2 by any suitable means, as for example the bolts 5^b. Externally of the casing 2 a chain wheel 6 (or other drive member) is mounted fast upon 60 the reduced projecting end portion 4 of the head 3. For rigidly connecting said chain wheel to the part 4, bolts 6^a or the like may be employed. 7 is a sleeve which snugly embraces the cylindrical head 3 within the casing 2, said sleeve being formed with a port 8. When said port registers with the port 3^a of the head 3, steam or the like may flow from the casing 2 into the head 3 and thence to the blower pipe. When said sleeve is rotated to 65 shift the port 8 out of registration with the port 3^a the cleaning fluid is cut off from the blower pipe (see Figure 2). The sleeve 7 carries an outwardly projecting lug 9 which is engageable with a pin 10 carried by the 70 casing 2 to limit rotation of said sleeve in either direction. Thus, if the ports 8 and 3^a initially occupy the non-registering relation shown in Figure 2 and the chain wheel 6 is driven to the right, the sleeve 7 will, during 75 the major portion of the revolution, turn in unison with the head 3; this following from the fact that said sleeve snugly fits upon said head and is under an external steam pressure tending to somewhat increase the firmness of 80 contact with the head 3. When said head has been actuated through almost a revolution the lug 9 will engage an opposite side of the stop pin 10, as is illustrated in Figure 3. This will compel the sleeve 7 to remain stationary 85 and a slight further actuation of the head 3 to the right will register the ports 3^a and 8 as is illustrated in Figure 3. A screw 10^a carried by the head 3 and outwardly projecting into the port 8 acts as a stop to limit rotative 90

95

100

travel of said head when the ports 3^a and 8 are properly registered. Preferably the right hand edge of the port 8 is notched slightly as indicated at 11 to accommodate the head of the screw 10^a when the ports are in registration. The operator now reverses the direction of drive of the chain wheel 6 so that the head 3 and blower 1 are actuated to the left. The sleeve 7 and head 3 turn in unison until the lug 9 encounters the stop pin 10, as is illustrated in Figure 4. A slight further actuation of the head 3 to the left shifts the port 3^a out of registration with the port 8 whereupon the screw 10^a engages the edge 12 of the port 8 and thus stops further rotation to the left. The described cycle of the operation may be repeated as often as is necessary. 12^a designates an inlet for steam or other cleansing fluid to the casing 2. 12^b is a whistle mounted in the closed end 4^a of the head 3, which whistle sounds as long as steam is entering the blower pipe 1 and thus acts as a safeguard to prevent the valve being left in open position.

Referring now to that form of the invention disclosed in Figures 5, 6 and 7, 13 is a rotary blower pipe and 14 is a casing having its ends provided with opposed packed bearings 14^a in one of which said pipe is journaled. Within said casing the pipe 13 is screw threaded or otherwise rigidly connected to one end of a cylindrical head 15 having the port 15^a, the other end of said head being screw threaded to a short length of pipe 16 journaled in the other bearing 14^a and projecting exteriorly of the casing to carry a chain wheel 18, the projecting end of said pipe 16 being closed, as indicated at 18^a. Within the casing 14 the head 15 is snugly embraced by a sleeve 19 in which is formed a port 20 which, when registered with the port 15^a of said head, provides for admission of steam or the like to the blower pipe 13 from the casing 14. Said sleeve 19 carries an outwardly projecting pin 21 which in two different positions of longitudinal adjustment of said sleeve is adapted upon rotation of the sleeve in said positions to respectively engage pins 22 or 23. The ends 50 of the sleeve 19 are respectively formed with oppositely projecting teeth 24 and 25, each having one side parallel to the axis of the sleeve and its other side gradually bevelled. The head 15 carries upon its respective ends pins 24' and 25' which are respectively engageable with the teeth 24 and 25 to shift the sleeve 19 endwise. 26 is an inlet for steam or the like to the casing 14.

If desired, an additional threaded hole 23' 60 may be formed in the casing 14 as illustrated in Figure 7 of the drawing. This hole is adapted to receive a pin similar to the pins 22 and 23 to permit an adjustment in the time of operation of the valve with respect to the 65 movement of the blower unit. A suitable

plug 23" may be provided to close the plug when the same is not in use.

Considering now the operation of the described construction, it is to be understood that, by means of the chain wheel 18, the head 15 and blower pipe 13 are rotatively actuated in a constant direction instead of being rocked back and forth as in the first described construction. Assuming that the ports 15^a and 20 are initially registered, as illustrated in Figure 7, and that the blower is being actuated to move in a clockwise direction, initially the pin 21 will encounter the pin 22 as indicated in Figure 5, the sleeve 19 being thus held stationary. Continued rotation of the head 15 will, after a predetermined rotative advance, cause the pin 24' to engage the bevelled edge of the tooth 24 forcing the sleeve 19 to the right so that the pin 21 clears the pin 22. The rotative advance of the head 15 during the interval of rest of the sleeve 19 will shift the port 15^a of said head out of registration with that of the sleeve so that the supply of cleaning fluid to the blower pipe will be cut off. After a predetermined further rotation of the head 15, the pin 21 will encounter the stop pin 23 again halting rotation of the sleeve 19. During this period of rest of said sleeve, the advance of the head 15 will again shift the port 15^a into registering relation with the port 20. When such relation has been established, the pin 25' will engage the bevelled edge of the tooth 25 shifting the sleeve 19 to the left so that the pin 21 clears the stop pin 23 and the sleeve is again carried forward by the rotating head. The described cycle of operation may be repeated as long as is necessary.

In that form of the invention illustrated in Figures 8, 9 and 10 there is shown a rotative blower pipe 27 and a chain wheel 28 driving said blower pipe through a cylindrical head 29, said head having inlet ports 30, the valve casing 31 enclosing said head and a sleeve 32 snugly embracing said head within said casing, all of said parts being arranged substantially as hereinbefore described. The distinctive feature of this construction, however, lies in the fact that an endwise movement of the sleeve 32 is employed to control the ports 30. Thus, said ports are circumferentially elongated and are adapted to register with similarly elongated ports 33 in the sleeve 32. Upon the end walls of the casing 31 there are mounted reverse cam members 34 and 35 which are engaged by lugs 36 integrally projecting from the ends of the said sleeve. To insure rotation of the sleeve 32 in unison with the head 29 it is preferred to provide an inwardly projecting pin 37 upon said sleeve to engage in a longitudinal groove 38 externally formed in the head 29.

In the operation of the described construction the sleeve 32 turns in unison with the

blower pipe 27 when the latter is rotatively actuated but during each revolution said sleeve is subjected, through engagement of the lugs 36 by the cams 34 and 35, to an endwise sliding movement which causes the ports 30 and 33 to register during a predetermined portion of such revolution so that at such times steam or the like is admitted to the blower pipe 27 from the casing 31. 5 During the remaining portion of each revolution said ports are non-registering and the supply of cleaning fluid to the unit is cut off.

Considering now the alternative construction illustrated in Figures 11, 12, 13 and 14, 15 40 is a rotary blower pipe equipped with a chain wheel 41, the latter being connected to said pipe by a cylindrical head 42 having the intake ports 43 for steam or the like. 20 The ported portion of said head is enclosed within a valve casing 44 and within said casing a sleeve 45 snugly embraces said head, said sleeve being formed with ports 46 adapted, in one position of endwise movement of said sleeve, to register with the ports 43. In this construction the sleeve 45 is restrained from rotation by engagement of a pin 47 outwardly projecting from said sleeve between a pair of lugs 48 internally formed 25 upon the casing 44. Thus, said sleeve 45 is free to slide lengthwise upon the head 42 but cannot turn with said head. As a provision for shifting said sleeve lengthwise to establish or discontinue the registering relation between the parts 46 and 43 teeth 49 30 are formed oppositely upon the respective ends of said sleeve, each having one edge parallel with the axis of said sleeve, the other edges of said teeth being correspondingly bevelled, as is best seen in Figure 12. 35 Upon the head 42 there is provided a pair of pins 50 for respective engagement with the bevelled edges of the teeth 49.

In the operation of this embodiment of 40 the invention, the ports 46 and 43 register during a predetermined portion of each revolution of the head 42, the circumferential extent of the ports 46 sufficiently exceeding that of the ports 43 to maintain a registered 45 relation during this period. One of the pins 50 will then encounter the corresponding cam tooth 49 and shift the sleeve endwise to cut off registration between the sleeve ports and those of the head. After turning to the 50 proper predetermined portion of a revolution with the fluid supply thus cut off from the blower, the other pin 50 encounters the other lug 49 and the sleeve is shifted endwise to register the ports 46 and 43.

60 It is a feature of each of the described valve constructions that the rotative actuation of the blower is utilized also to control opening and closing of the valve so as to maintain the steam supply only during a desired predetermined portion of each revolution.

lution or of each angular advance in case the unit is of a rocking type.

The word "rotative" as applied herein and in the following claims is considered to signify adapted to turn through either a revolution, a fraction of a revolution, or a plurality of revolutions. Further, while the invention has been described as comprising a boiler cleaner adapted for cleaning parts of a boiler, it will be apparent that the invention may be embodied in a cleaning device for similar types of apparatus. It is to be therefore understood that the word "boiler" wherever used in the specification or claims is to be construed as meaning a heat transfer apparatus or fluid heater of any character, while the term "boiler cleaner" is to be construed as meaning a cleaner for any such apparatus.

What we claim as our invention is:—

1. In a boiler cleaner, the combination with a casing, of a rotative cleaning unit having a portion disposed within said casing, said unit having a circumferentially opening port, a ported sleeve snugly embracing the ported portion of said unit, said sleeve being adapted to normally close the port in said unit during the periods of non-use of the boiler cleaner, means for angularly advancing said unit, and means for shifting said sleeve during a predetermined angular advance of said unit to register said ports for a desired proportion of said advance.

2. In a boiler cleaner, the combination with a casing, of a rotative cleaning unit having a portion within the said casing, said unit having a circumferential inlet port, a ported sleeve snugly embracing the ported portion of said unit and frictionally constrained to travel therewith, said sleeve being adapted to normally close the port in said unit during the periods of non-use of the boiler cleaner, and means for shifting said sleeve through the angular advance of the unit to register the two said ports during a predetermined portion of said advance.

3. In a boiler cleaner, the combination with a delivery head for a cleaning fluid, of a rotative cleaner unit having an inlet port within said head, a ported sleeve surrounding the ported portion of said unit within said delivery head, and means for rotating said unit, said sleeve being movable by said unit during predetermined portions of the angular advance of the unit to control registration of the ports of the unit and sleeve.

4. In a boiler cleaner, the combination with a delivery head for a cleaning fluid, of a rotative cleaner unit having an inlet port within said head, a ported sleeve surrounding the ported portion of said unit within said head and adapted to normally close the port in said unit during the periods of non-use of the boiler cleaner, means for rotating said unit, the sleeve being frictionally constrained

to rotate with the unit, and means carried by said head acting upon the sleeve during a predetermined portion of the angular advance of the unit to shift the sleeve to establish registration of the port thereof with that of the unit.

5. In a boiler cleaner, the combination with a delivery head for a cleaning fluid, of a rotative cleaner having an inlet port within said head, means for rotating said unit, and a ported control element for the port of said unit adapted to normally close the port in said unit during the periods of non-use of the boiler cleaner, frictionally constrained to rotate with the unit, and means carried by said head engaging said control element during a predetermined portion of the angular advance of the unit to establish registration of the ports of the unit and said control element.

6. In a boiler cleaner, the combination with a delivery head for a cleaning fluid, of a rotative cleaner unit having an inlet port within said head, a ported sleeve surrounding the ported portion of the unit within said head and adapted to normally close the port in said unit during periods of non-use of the boiler cleaner, means for rotating said unit, and coacting means upon the said unit and said head controlling said sleeve and registering the port thereof with that of the unit during a predetermined portion of the angular advance.

7. In a boiler cleaner, the combination of a rotative cleaning unit having a plurality of jets for discharging steam or the like against the surfaces to be cleaned, said unit having a lateral inlet port, and a movable member adapted to normally close the port in said unit during the periods of non-use of the boiler cleaner and having a port adapted to register with the port in said unit.

8. In a boiler cleaner, the combination of a rotative cleaning unit having a plurality of jets for discharging steam or the like against the surfaces to be cleaned, said unit having an inlet port, and a movable member engaging said unit and adapted to normally close the port in said unit during the periods of non-use of the boiler cleaner, and having a port adapted to register with the port in said unit, said member rotating with said unit after said ports are in registration.

9. In a boiler cleaner, the combination with a delivery head for a cleaning fluid, of a rotative cleaner unit provided with a discharge nozzle and having an inlet port within said head, a ported element, means of moving said ported element to register with said inlet port, after a predetermined movement of the cleaner unit, for supplying cleaning fluid to said discharge nozzle, and means for moving said ported element out of registry with said inlet port after a further predetermined movement of the cleaner unit.

10. In a boiler cleaner, the combination with a delivery head for a cleaning fluid, of a rotative cleaner unit provided with a discharge nozzle and having an inlet port within said head, a ported element adapted to register with said inlet port at times for supplying cleaning fluid to said discharge nozzle, means controlled by the rotative movement of the cleaner unit for moving said ported element out of registry with said inlet port after a predetermined movement of the cleaner unit.

11. In a boiler cleaner, the combination with a delivery head for a cleaning fluid, of a rotative cleaner unit provided with a discharge nozzle and having an inlet port within said head, a ported element adapted to register with said inlet port at times for supplying cleaning fluid to said discharge nozzle, means controlled by the rotative movement of the cleaner unit for moving said ported element out of registry with said inlet port after a predetermined movement of the cleaner unit, and means controlled by the rotative movement of the cleaner unit for moving said ported element back into registry with said inlet port after a further predetermined movement of the cleaner unit.

12. In a boiler cleaner, the combination with a delivery head for a cleaning fluid, of a rotative cleaner unit having an inlet port within said head, a ported member overlying the ported portion of the unit within said head and adapted to normally close the port in said unit during the periods of non-use of the boiler cleaner, means for rotating said unit and coacting means upon the said unit and said head controlling said ported member and registering the port thereof with that of the unit after a predetermined portion of the angular advance of said unit.

13. In a boiler cleaner, the combination with a cleaning fluid supply pipe, of a rotative cleaning unit having an inlet port for the admission of cleaning fluid to said unit, a ported member adapted to register with the inlet port of said unit, and means for rotating said unit, said member being movable by said unit during predetermined portions of the movement of said unit to control registration of the ports of the unit and member.

14. In a boiler cleaner, the combination with a cleaning fluid supply pipe, of a movable cleaning unit having an inlet port for the admission of cleaning fluid to said unit, a ported sleeve snugly embracing the cleaning unit and adapted to normally close the port in said unit, means for moving said unit, and means operable upon a predetermined movement of said unit to shift said sleeve to effect a registration of the port in the sleeve with the port in the unit.

15. In a boiler cleaner, the combination with a cleaning fluid supply pipe, of a rotative cleaning unit having an inlet port for

the admission of cleaning fluid to said unit, a ported member adapted to normally close the port in said unit, means for rotating said unit and means automatically operable upon 5 a predetermined rotation of said unit for shifting the said ported member to effect a registration of the port thereof with the inlet port of the said unit.

16. The combination with a blower element 10 and means for actuating the same, of a sliding valve for controlling the admission of cleaning fluid to said blower element, and cam members for automatically controlling the movement of said valve to open and closed 15 positions upon the actuation of said blower element.

17. The combination with a rotatable blower element and means for rotating the same throughout an arc of at least 360°, of a valve 20 for controlling the admission of cleaning fluid to said blower element, and means including a relatively stationary cam member for moving said valve to open and closed positions upon the rotation of said blower 25 element.

18. In a boiler cleaner, the combination with a delivery head for a cleaning fluid, of a rotative cleaner unit having an inlet port within said head, a valve within said head 30 for controlling the flow of cleaning fluid through said port and cam members within said head for automatically controlling the movement of said valve to open and closed positions upon the actuation of said blower 35 element.

19. The combination with a rotatable blower element and means for rotating the same, of a sliding sleeve valve for controlling the admission of cleaning fluid to said blower 40 element and means including relatively stationary cam members for moving said valve to open and closed positions upon the rotation of said blower element.

20. The combination with a movable blower 45 element having an inlet port, of a sleeve valve controlling the flow of cleaning fluid through said port, and means operable upon movement of said blower element to move said sleeve valve to control the admission of cleaning fluid to the blower element in dependence upon the movement thereof.

21. The combination with a movable blower element, of a sleeve valve movable with said blower element and relative thereto for controlling the flow of cleaning fluid to the blower element, and means operable upon movement of the blower element to move the said sleeve valve relative to the blower element.

22. The combination with a movable blower element having an inlet port, of a ported member for controlling the flow of cleaning fluid through said inlet port, and means operated upon movement of said blower element 55 to move said ported member to control the

registration of the port therein with the port in said blower element.

23. The combination with a movable blower element, of a ported member movable with said blower element and relative thereto for 70 controlling the admission of cleaning fluid to said blower element, and means operable upon movement of said blower element to move the said ported member relative to the blower element.

24. The combination with a movable blower element, of a valve member movable with said blower element, said valve member being also movable longitudinally of the blower element to control the admission of cleaning fluid to the same, and means operable upon movement of the blower element to effect a longitudinal movement of the valve.

25. The combination with a rotatable blower element, of a valve member rotatable with the said blower element and also movable longitudinally thereof to control the admission of cleaning fluid to the blower element, and means operable upon rotation of the blower element to effect a longitudinal 90 movement of the valve member.

26. The combination with a movable blower element, of a valve member movable with said blower element and also movable relative thereto for controlling the admission of 95 cleaning fluid to the blower element, and means including a pair of cam members for effecting a movement of the valve member relative to the blower element.

27. The combination with a movable blower element, of a member embracing the said blower element and movable with the same, said member being also movable relative to the blower element for controlling the flow of cleaning fluid to the blower element, and means operable upon movement of the blower element to effect a movement of the said member relative to the blower element.

28. The combination with a movable blower element having an inlet port, of a sleeve valve for controlling the flow of cleaning fluid through said port, means on said blower element operating upon relative movement between the valve and blower element to shift said sleeve valve longitudinally of said blower element to control the flow of cleaning fluid to the blower element, and means for restraining said sleeve valve against movement with said blower element.

29. The combination with a movable blower element having a laterally opening inlet port, of a sleeve valve embracing said blower element for controlling said port, means operable upon movement of said blower element for shifting said sleeve valve longitudinally of said blower element, and means for restraining said sleeve valve against movement with said blower element.

30. The combination with a rotatable blower element having an inlet port, of a

ported member for controlling said port, means operable upon movement of said blower element for shifting said ported member longitudinally of the blower element, and means for restraining said ported member against movement with said blower element.

31. The combination with a rotatable blower element, of a sleeve valve for controlling the flow of cleaning fluid to said blower element, means operable upon rotation of said blower element to shift said sleeve valve longitudinally of said blower element, and means for restraining said sleeve valve against rotation with said blower element.

32. The combination with a movable blower element having an inlet port, of a member carried by said blower element for controlling the flow of cleaning fluid through said inlet port, means on said blower element operating upon relative movement between said member and blower element to shift said member longitudinally of said blower element to control the flow of cleaning fluid to the blower element, and means for restraining said member against movement with said blower element.

33. The combination with a rotatable blower element having an inlet port, of a member carried by said blower element for controlling the flow of cleaning fluid through said port, means operable upon rotation of said blower element to shift said member longitudinally of said blower element, and means for restraining said member against rotation with said blower element.

34. The combination with a movable blower element having an inlet port, of a member carried by said blower element and normally movable therewith for controlling said port, and means for holding said member against movement with said blower element to effect a closing or opening of said port.

35. The combination with a movable blower element having an inlet port, of a ported member carried by said blower element and normally movable therewith, and means for periodically holding said ported member against movement with said blower element to control the registration of the port in said ported member with the inlet port in said blower element.

36. The combination with a rotatable blower element having an inlet port, of a sleeve valve normally rotatable with said blower element, and means periodically operable to restrain said sleeve valve against rotation with said blower element to control opening and closing of said port by said sleeve valve.

37. The combination with a rotatable blower element having an inlet port, of a ported sleeve surrounding the ported portion of said blower element and normally rotatable therewith, means for rotating said blow-

er element, and means periodically operable to hold said ported sleeve against rotation with said blower element to control registration of the port in said sleeve with the inlet port in said blower element.

38. In a boiler cleaner, the combination of a movable blower element, means for controlling the flow of cleaning fluid to said blower element including a valve seat member movable with the blower element and a valve member mounted for limited movement relative to said valve seat member for controlling the flow of cleaning fluid through the same, and means for moving said blower element, said valve seat member being movable with said blower element and relative to said valve member upon movement of the blower element to provide for the admission of cleaning fluid to the blower element.

39. In a boiler cleaner, the combination of a rotatable blower element, a valve seat member rotatable with the blower element, a valve member engageable with said valve seat member and mounted for limited movement with respect thereto, and means for rotating said blower element, said valve seat member being movable relative to said valve member upon rotation of the blower element to admit cleaning fluid to the blower element.

40. In a boiler cleaner, the combination of a blower head, a blower element rotatably journaled in said head, means for controlling the flow of cleaning fluid to said blower element including a valve seat member movable with the blower element and a valve member engageable with said valve seat member, means mounting said valve member in said head for limited movement therein, and means for rotating said blower element, the rotation of said blower element effecting a movement of said valve seat member relative to said valve member to admit cleaning fluid to the blower element.

41. In a boiler cleaner the combination of a rotatable blower element, a valve seat rotatable with the blower element, a cylindrically surfaced valve free to float with the valve seat for controlling the flow of cleaning fluid to the blower element, means for restraining said valve against rotation with the blower element, and means for rotating the blower element, said valve seat being rotatable with the blower element upon rotation of the latter to admit cleaning fluid to the blower element.

42. In a boiler cleaner the combination of a blower head, a rotatable blower element extending into said head, a valve seat rotatable with the blower element, a cylindrically surfaced valve free to float with the seat for controlling the flow of cleaning fluid from the blower head to the blower element, said valve being spaced from the inner surface of the head whereby the pressure of the cleaning fluid in the head tends to hold the valve to its seat, means for restraining said valve against

rotation with the blower element, and means for rotating the blower element, said valve seat being rotatable with the blower element upon rotation of the latter to admit cleaning fluid to the blower element.

43. In a boiler cleaner, the combination of a rotatable blower element, a valve seat rotatable with the blower element, a cylindrically surfaced valve free to float with the valve seat but fixed against movement longitudinally of the element for controlling the flow of cleaner fluid to the blower element, means for restraining said valve against rotation with the blower element, and means for rotating the blower element, said valve seat being rotatable with the blower element upon rotation of the latter to admit cleaning fluid to the blower element.

44. In a boiler cleaner the combination of a blower head, a rotatable blower element extending into said head, a valve seat rotatable with the blower element, a cylindrically surfaced valve free to float with the seat but fixed against movement longitudinally of the element for controlling the flow of cleaning fluid from the blower head to the blower element, said valve being spaced from the inner surface of the head whereby the pressure of the cleaning fluid in the head tends to hold the valve to its seat, means for restraining said valve against rotation with the blower element, and means for rotating the blower element, said valve seat being rotatable with the blower element upon rotation of the latter to admit cleaning fluid to the blower element.

45. In combination, a movable blower element, a valve for controlling the flow of cleaning fluid to said blower element, a member movable with said blower element and so associated with said valve that upon a predetermined movement of said blower element in one direction the member moves said valve to open position, and a second member movable with said blower element and so associated with said valve that upon a further predetermined movement of the blower element in the same direction this second member closes said valve.

46. In a boiler cleaner, the combination with a movable blower element, of a valve for controlling the admission of cleaning fluid to said blower element, and a plurality of members movable with said blower element and so associated with said valve that upon continuous movement of said blower element in the same direction they operate to successively open and close said valve.

In testimony whereof we affix our signatures.

CURTIS L. HOWSE.
